AUTOMATIC BUOYANCY CONTROL SYSTEM

Richard C. Wolfe, United States Navy, Los Angeles, Calif., and Thomas C. Boyle, Washington, D. C., assignors to the United States of America as represented by the Secretary of the Navy

Application November 30, 1945, Serial No. 632,090

3 Claims. (Cl. 114—20)

(Granted under the act of March 3, 1883, as amended April 30, 1928; 370 O. G. 757)

I

This invention relates to buoyancy control systems, and particularly to improved means for automatically imparting positive buoyancy to objects, such as underwater torpedoes, that may normally or under predetermined conditions operate with negative buoyancy, yet to which it is desired to impart positive buoyancy after a predetermined time, or in the event predetermined conditions occur, to insure flotation of the device and thus facilitate its recovery.

Torpedoes normally operate with slight negative buoyancy, and must be subjected to one or more tests or exercise runs to permit checking their performance and the making of any necessary adjustments, prior to the final attachment of the explosive-loaded war head and the approval of the torpedo for use in warfare. Such exercise runs are made with a simulated war head, containing no explosive and ordinarily referred to as an "exercise head," attached in place of the war head. The exercise head contains suitable apparatus by which the performance of the torpedo during exercise runs is determined and recorded. In torpedoes of that class wherein air under pressure is expended during operation, and wherein the exercise head carries a quantity of water sufficient to represent the weight of the explosive contained in the corresponding war head, it has been customary to provide automatic blowing means whereby, when the air pressure falls to a predetermined value, a certain proportion of the remaining air is directed into the exercise head, to expel the water ballast therefrom, impart positive buoyancy, and thus insure flotation of the torpedo upon completion of the run. This system is subject to certain shortcomings in that, should the torpedo be stopped or become lodged or imbedded in the bottom in such manner that the propelling machinery is arrested and the air cannot be sufficiently exhausted, the automatic ballast blowing mechanism above referred to fails to function.

An important object of the present invention, therefore, is to provide an improved automatic blowing system so constructed and arranged that not only does automatic blowing of the ballast from the exercise head occur when the air pressure falls to a predetermined value, as previously mentioned, but automatic blowing is also induced, regardless of the air pressure, in event the torpedo sinks below a predetermined set depth. A related object is to provide such a dual system incorporating controlling means responsive both to air pressure and to the hydrostatic pressure resulting from the depth of the torpedo, wherein

5 a single valve serves to control the flow of the ballast blowing air in response to both of the above-noted factors, and the supplemental or hydrostatic controlling mechanism makes use of many of the parts already incorporated in the presently used air pressure-responsive system.

Another object of the present invention is to provide such a hydrostatic system wherein the parts subjected to sea water pressure are entirely 10 outside and sealed from the interior of the exercise head, so that no water can gain access to the interior of the torpedo by reason of the incorporation of the mechanism of the invention.

Still another object is to provide, in conjunction with a head blowing system of the character outlined, supplemental sealing means so designed that the portions to which sea water is admitted in order to provide the hydrostatic actuating pressure are completely sealed until the time of 20 launching of the torpedo.

Other objects and advantages will be apparent upon consideration of this disclosure in its entirety.

In the drawings:

25 Figure 1 is a sectional perspective view of valving and controlling means constructed in accordance with the invention, fragmentarily showing adjacent portions of a torpedo within which our improved buoyancy control system is installed.

30 Figure 2 is a substantially central longitudinal sectional view of the apparatus with the parts in the positions they occupy after actuation thereof by hydrostatic pressure;

35 Figure 3 is an elevational view taken as indicated by the line and arrows 3—3 of Figure 2, the supporting flange and a part of the upper portion of the casing for the hydrostatic mechanism being shown in section;

40 Figure 4 is a top plan view of the mechanism, the sea water valve being shown in longitudinal section;

45 Figure 5 is a sectional detail taken substantially on the line 5—5 of Figure 4 and looking in the direction of the arrows;

50 Figures 6, 7, 8 and 9 are detailed perspective views of components of the sea water valve and trip mechanism, a portion of the trip plate being broken away in Figure 8;

55 Figure 10 is a cross sectional view taken substantially on the line 10—10 of Figure 2 and looking in the direction of the arrows;

Figure 11 is a vertical sectional detail taken substantially on the line 11—11 of Figure 1 and looking in the direction of the arrows;

2

Figure 12 is a horizontal sectional plan view taken substantially on the line 12—12 of Figure 3 and looking in the direction of the arrows, and

Figure 13 is a sectional view of the water discharge check valve for automatic blowing as when the air pressure falls to a predetermined point.

With reference to the drawings, the reference character 15 designates the shell or hull of the exercise head of a torpedo, the remaining portions of which, since they form no part of the present invention, are not shown. As previously indicated, when an exercise run is to be made the shell of the exercise head is filled, manually or by other suitable means, with a sufficient quantity of water ballast to correspond to the weight of the explosive contained in the war head. A quantity of air under high pressure is also contained in a portion of the torpedo (not shown in the present drawings), connection to this supply being made by a tube 20.

The water-containing portion of the exercise head is closed at its after end by means of a bulkhead 22, the tube 20 extending through a suitably sealed joint 23 in this bulkhead as shown in Figure 1. A portion of the tube 20 may be coiled, as indicated at 20', to provide resilience under sudden pressure surges, and to permit connections to be made with the exercise head disassembled, the terminal portion of the coil being coupled as indicated at 24 to the lower extremity of a vertically disposed valve body or casing suspended within a ballast chamber 16. The air pressure constantly acts upon the lower end of a valve stem 27 longitudinally slidable in a central or main section 25 of the valve casing. A compression spring 28 coiled about a portion of the valve stem 27 constantly urges the valve toward opened position, while air pressure, as will be seen, tends to maintain the valve closed. The spring 28 may be designed to open the valve when the air pressure has fallen to a value in the neighborhood of five to six hundred pounds per square inch, while the initial air pressure may be in the neighborhood of 2800 pounds per square inch, although these values are, of course, merely representative. The spring 28 reacts at its lower end against an abutment 29 affixed to the valve stem 27 and at its upper end against a combined closure and spring retaining plug 30. As shown in Figures 1 and 2, the air is admitted through a strainer 26 into a chamber 31 contained in a lower section 25' of the valve casing and is then conducted through a passage 32 into a chamber 33 which lies below the head of the valve stem 27. The valve is provided with a plurality of longitudinally spaced piston sections 34, 35, 36, the lower and first mentioned of which constitutes the head against which the direct flask pressure acts as previously indicated, while two valve chambers 37, 38 between the piston sections are serially connected by two air passages 40, 41, the passage 40 communicating with the chamber 33. These passages are somewhat restricted in size, so that when pressure is first introduced into the chamber 33, it builds up against the head 34 sufficiently to close the valve against the effort of the spring 28, the air being unable to escape through these passages rapidly enough to prevent a sufficient build up of pressure to close the valve. When the pressure falls to such point that it is overcome by the spring 28 and the valve is opened, the air escapes through the passages mentioned, around the piston 36, and out through the lateral passages 39 into the water ballast

compartment 16, displacing the water, whence it escapes through a water discharge check valve the construction of which is shown in Figure 13.

As indicated in Figure 13, the discharge valve body, secured to the bottom of the hull 15 and designated 43, is of generally annular form, provided with a plurality of relatively large outlet apertures 44 surrounded by a seat 45 against which a sealing disc or washer 46 is urged by a thrust spring 47, with a pressure which may correspond to a ballast water pressure in the neighborhood of 400 pounds per square inch. The discharge valve is thus opened when the combined air and water pressure within the compartment 16 exceeds this value, and the water then escapes through the orifices 48 in the combined spring-supporting and closure plate 49 which is supported across the opening (undesignated) in the hull in which the discharge valve is mounted.

An upper section 252 of the valve casing 25 is threaded into or otherwise supported by a collar 51 carried by and shown as integral with a pair of laterally spaced vertically disposed webs 52 attached at their upper ends to an annular top 25 casing portion 53. Casing portion 53 is shown as of cupped form, provided with a top flange 54 which is preferably accurately ground to insure an effective water seal, and tightly clamped and supported between a flanged ring 55 and a clamping ring 56. Ring 55 is seated at its top against and accurately fits the interior of the hull 15 surrounding the opening 17 therein. Clamping ring 56 is tightly forced down upon and also sealed against the flange 54 by the screws 57, a portion 58 (Fig. 3) of ring 56 being contoured to overhang the hull 15 and to be tightened there against when the screws 57 are taken up.

The hydrostatically actuatable means is arranged to augment the valve-opening force exerted by spring 28 in direct proportion to the hydrostatic head. These parts are so designed and proportioned that the torpedo will reach a certain depth after an initial delay determined by the size of the chamber 33 and/or the orifices 48. This delay is calculated to enable the torpedo to reach a set depth after its initial dive. The auxiliary opening force thus exerted on the valve is sufficient to overcome the full flask air pressure and open the valve 27, thus admitting the full air pressure to the compartment 16, blowing the water therefrom in the manner previously indicated, and creating positive buoyancy in the manner outlined above.

An extension 27' of the valve stem 27 projects upwardly from the retaining plug 30 into the space between the webs 52 in position to be contacted by the lower arm 61 of a bellcrank, the other upwardly extending arm 62 of which is movable under the influence of the hydrostatic mechanism. The hub of the bellcrank is journaled in the webs 52 by a cross shaft 64 while the upper end of the arm 62 is attached to a pair of overcenter links 65, 66. These are centrally articulated by a pin 67, the link 65 being pivoted at its other end to the extremity of the arm 62, while the outer end of the link 66 is journaled upon a pin 68 extending between the webs 52.

A pair of relatively heavy overcenter springs 70 reacts against the lower arm 61 of the bellcrank, the lower ends of the springs being hooked to the extremities of a supporting rod 71 carried by a bracket 72 projecting outwardly and downwardly from the valve supporting collar 51, while the upper ends of the springs are similarly connected by a pin 73 to the outer end of the bell-

crank arm 61. A stop 74 may be provided to limit the downward movement of the arm 61 and thus of the valve 27, the stop 74 being formed as a screw mounted in the arm and adapted to bear against the top of the bracket 72.

Movement of the linkage 65-66 is controlled by a stem 75 actuatable by a bellows diaphragm 76 of the "Sylphon" type. The rod 75 is vertically movable in an internal sleeve 77. The sleeve 77 projects into the bellows and is flanged at its top to permit supporting thereof in the cupped casting portion 53 by means of the same screws 78 that are employed to support the top supporting flange 79 of the bellows diaphragm. A top plate 80 extends across the flanged upper end of the sleeve 77 and is also positioned by the screws 78. The stem 75 carries means near its lower end for tightly clamping it to and sealing it against the end of the bellows 76, while the lower end of the stem projects beyond the bellows in position to operate the overcenter linkage 65-66, near the central joint provided by the pin 61. Sealing of the stem to the bellows is completed by a stem-carried resilient packing washer 82 which functions as a piston, which is compressed against the inside of the end of the bellows by an abutment washer 83, attached to the stem 77 outside the bellows and soldered or otherwise sealed with respect to the latter bellows as well as with respect to the stem. Within the bellows the stem passes through an opening 84 in the end of the sleeve 77. A nut or head 85 on the threaded lower end of the stem 75 serves as an adjustable head for engaging the link 65 and is adapted to be locked in any position to which it is adjusted, by means of a cotter pin 86.

An externally threaded extension 88 is screwed on to the upper threaded end of the stem 75 and projects upwardly into an inverted cupped bearing boss 90 mounted upon but rotatable in the head 53 in axial alignment with the stem 75. A cross pin 91 extends through and projects laterally from the upper end of the extension 88, the ends of the pin extending into vertical slots 92 in the boss 90. The extension 88 is thus rotatable for adjustment by turning the knob-like boss 90. A flange 89 on the extension 88 serves as an abutment for a spring 95 housed in the sleeve 77 and loosely surrounding the stem 75, the lower end of the spring bearing against the bottom flange of the sleeve 77 so that the reaction of the spring tends to urge the head 85 and the attached stem upwardly, and the bellows to the contracted position. When the head 85 is thus raised and the bellows contracted, the overcenter linkage is arranged, in the manner indicated in Figure 1, with the center of the pin 67 above a line connecting the pin 68, 69, the degree of upward movement of the linkage and of the stem being limited by the sealing washer 82 which is compressed against sleeve 77. The bell crank is then rocked slightly to the right, the arm 61 being lifted from the extension 27' of the valve stem 27, and the valve 27 being then free to move upwardly to the fully closed position in which it is normally maintained by the flask air pressure.

If the hydrostatic mechanism does not function, the valve 27 is controlled and movable entirely by the interaction of the spring 28 and flask air pressure in the normal manner and the arm 61 remains raised and free of the valve stem extension. If hydrostatic pressure rises sufficiently, however, the bellows is distended and the head 85 is driven downwardly until the pin 67 passes through the line connecting the

axes pins 68, 69, whereafter the linkage breaks to the position in which it is shown in Figure 2, the bell crank arm 61 being rocked downwardly under the influence of the springs 70, and forcing the valve stem 27 downwardly to open the valve, the effort of the springs 70 being sufficient to overcome the flask pressure, so that the valve is opened positively and without regard to the existing flask pressure.

10 The space above the top flange of the sleeve 77 is exposed to the sea, and pressure communication with the interior of the bellows is provided by a passage 95 in a valve body 100 which forms a part of the top closure of the bellows. 15 In order to prevent fouling if used in a flooded submarine tube and corrosion of the parts and of the passage 95 prior to firing, the passage may be sealed by valve means adapted to be opened, either manually when used above water or automatically when used in a submarine at the time of firing, the upper end of the passage 95 being thus opened for admission of pressure to the interior of the bellows. The valve body is attached to the bellows top plate 79, the lower end of internal passage 95 communicating with the free air space directly above the bellows and thus with the interior of the bellows. Passage 95 terminates at its upper end in a port 96 forming the open end of a projecting hollow boss 101, against which a resilient valve pad 102 carried by a valve element 103 is adapted to be pressed to seal the port. The valve element 103 is slidably mounted upon the boss 101, a plurality of orifices 104 in the valve body being provided to admit sea water to the passage 95 when the valve is opened.

During storage and at all times when inserting the torpedo in a submarine tube and until the torpedo is fired, the valve 103 is held closed by the overcenter toggle linkage comprising the links 106, 107, the former being articulated to the valve body while the latter is pivoted to a fixed bracket 108. When the central pivot pin 109 is pushed downwardly below a line connecting the pins 110, 111, the valve is held tightly closed, the downward movement of the central pivot of the linkage being arrested with the links bearing against a portion of the base of the bracket 108, which is also secured to the top flange of the sleeve 77 by screws 78. The overcenter spring action is provided by a compression spring 112 housed within the valve 103 and reacting against the boss 101. A cam 113, also pivoted upon the central pin 109, is so shaped that when turned about such pin it may react against the plate 108 to push the central pivot of the linkage upwardly and overcenter, permitting full opening of the valve by the spring 112. A trip plate 114 attached to and shown as an integral continuation of the cam 113 projects outwardly in a direction substantially perpendicular to the flow of water past the torpedo, when the cam is in the position it occupies when the valve is closed, while as will be apparent from Figure 1, the velocity pressure developed by the flow of water is exerted in a direction to turn the cam in a manner to throw the linkage through center and release the valve for opening movement in the manner previously described. Thus when the torpedo is launched, the plate is thrown aft by the first impact with or rapid movement through the water, opening the valve 103 and permitting the water to enter the bellows 76. The bellows-operated trip head 85 is thereafter movable in response to increase of hydrostatic pressure which in turn depends upon the depth of the torpedo.

The supporting boss 90 for the spring abutment and extension section 88 is provided with a frusto-conic bottom portion 92 by which it is retained and journaled or swiveled in the plate 86. Extension 88 may thus be rotated, by turning the element 90 to change the initial tension of spring 95, thereby varying the effective force required to extend the bellows sufficiently to force the linkages 65, 66 over-center. Since the position of the pin 91 changes with the spring adjustment, calibrations as 120 may be provided upon the side of boss 90, adapted to cooperate with the pin 91, which is visible through the slot 92a, to indicate the depth setting of the hydrostatic mechanism.

While it will be apparent that the preferred embodiment of the invention herein disclosed is well calculated adequately to fulfill the objects and advantages primarily stated, it will be appreciated that the invention is susceptible to variation, modification, and change within the spirit and scope of the subjoined claims.

The invention herein described may be manufactured and used by or for the Government of the United States of America for governmental purposes without the payment of any royalties thereon or therefor.

We claim:

1. In a buoyancy control for a torpedo having a ballast chamber to contain water and having a conduit between said chamber and a supply of air under pressure, valve means interposed in the conduit yielding to the air pressure against it in one direction to maintain a closed position, and hydrostatic means to open the valve, said means comprising a bell-crank pivoted adjacent to the valve, spring means pressing the bell-crank toward one direction of turning so that one of its arms tends to push the valve to open position, an overcenter linkage connected to the other arm and being initially stationed to resist the pressure of the spring means, hydraulically displaceable means to break the linkage, said means comprising a rod directed toward the overcenter linkage, a piston carried by the rod to intercept seawater pressure, a spring-loaded valve initially closed to exclude seawater from the piston, and trip means coupled to the valve holding it closed against said spring loading, said trip means being actuatable by water impact upon launching the torpedo to release the valve.

2. In a buoyancy control for a torpedo having a ballast chamber to contain water and having a conduit between said chamber and a supply of air under pressure, valve means interposed in the conduit yielding to the air pressure against it in one direction to maintain a closed position, and hydrostatic means to open the valve, said means comprising a bell-crank pivoted adjacent

to the valve, spring means pressing the bell-crank toward one direction of turning so that one of its arms tends to push the valve to open position, an overcenter linkage connected to the other arm and being initially stationed to resist the pressure of the spring means, hydraulically displaceable means to break the linkage, said means comprising a rod directed toward the overcenter linkage, a piston carried by the rod to intercept seawater pressure, a spring-loaded valve initially closed to exclude seawater from the piston, an overcenter linkage connected to the valve and initially stationed to hold it closed against said spring loading, and a trip plate coupled to the last overcenter linkage, being actuatable by water impact upon launching the torpedo to break said last overcenter linkage thereby to release the valve.

3. In a buoyancy control for a torpedo having a ballast chamber to contain water and having a conduit between said chamber and a supply of air under pressure, valve means interposed in the conduit yielding to the air pressure against it in one direction to maintain a closed position, and hydrostatic means to open the valve, said means comprising a bell-crank pivoted adjacent to the valve, spring means pressing the bell-crank toward one direction of turning so that one of its arms tends to push the valve to open position, an overcenter linkage connected to the other arm and being initially stationed to resist the pressure of the spring means, hydraulically displaceable means to break the linkage, said means comprising a rod directed toward the overcenter linkage and having a threaded extension, a piston carried by the rod to intercept seawater pressure, a spring positioned to react against the threaded extension thereby to load the piston, a cupped bearing boss partly occupied by the extension, said boss having a swivel mount and a slot, and a pin in the extension projecting into the slot to establish a loose connection operable in adjusting the loading spring upon a turn of the bearing boss.
